UNITED STATES PATENT OFFICE.

ERNEST BUEROSSE, OF MILWAUKEE, WISCONSIN, ASSIGNOR OF ONE-THIRD TO
GEORGE BUEROSSE AND ONE-THIRD TO GEORGE J. BUEROSSE, BOTH OF MIL-
WAUKEE, WISCONSIN.
ELECTRIC-BRUSH HOLDER.

1,370,277.

Specification of Letters Patent.

Patented Mar. 1, 1921.

Application filed November 8, 1920. Serial No. 422,495.

To all whom it may concern:

Be it known that I, ERNEST BUEROSSE, a citizen of the United States, residing at Milwaukee, in the county of Milwaukee and

5 State of Wisconsin, have invented certain new and useful Improvements in Electric-Brush Holders, of which the following is a specification, reference being had to the accompanying drawing, forming a part
10 thereof.

This invention relates to brush holders for various types of electric generators and motors.

Its main objects are to automatically effect
15 and maintain uniform and true contact between the working faces of brushes and the commutators or collector rings; to prevent the brushes from shifting sidewise and to maintain them in proper position relative
20 to the commutators or collector rings without interfering with their free rocking movement sidewise and maintaining true contact with the commutators or collector rings; to avoid unequal and undue wear of
25 the brushes and of the commutators or rings with which they engage; and generally to improve the construction and operation of electric brush holders.

It consists in the construction, arrangement and combination of parts as herein-after particularly described and pointed out in the claims.

In the accompanying drawing like characters designate the same parts in the several figures.

Figure 1 is a side elevation of a brush holder embodying the invention in connection with the commutator or rotary contact member of an electric machine and a brush supporting yoke; Fig. 2 is an enlarged view partly in side elevation and partly in section of the brush holder, the section cutting the floating block or head of the holder on the line 3—3, Fig. 4; Fig. 3 is a plan view
40 of the brush holder with a portion of the brush supporting yoke; and Fig. 4 is a cross section of the brush holder showing the floating block or head and a brush attached thereto in elevation as viewed from the left
45 relative to Figs. 2 and 3.

Referring to Figs. 1 and 3, *a* designates a commutator, collector or rotary electric contact member of an electric machine, and *b* a brush supporting yoke angularly adjust-

able coaxially with the commutator and 55 provided with transverse studs *c*, preferably adjustable toward and from the axis of the commutator.

The brush holder constituting the present invention comprises a relatively stationary 60 block or head 1, and a floating brush supporting block or head 2, preferably made of electric conducting material such as copper or brass.

As shown in Figs. 2, 3 and 4, the blocks 65 or heads 1 and 2 are formed with aligned counterbored holes 4, in which the ends of closely coiled parallel helical springs 5 are seated, and are fastened by screws 6, engaging the convolutions of the springs adjacent their ends.

The springs form an elastic or resilient connection between the blocks or heads 1 and 2, which permits the floating block 2 to rock or tilt sidewise and to yield lengthwise in a direction approximately radial to the commutator or rotary contact member *a* of the electric machine with which the brush holder is used.

A carbon block or brush 8 is fastened to 80 the floating block or head 2 in any suitable manner, for example as shown, by a screw 9, passing through a hole in the brush and threaded in the block 2.

The block or head 1 is formed or provided 85 with a clamping collar 11, or other suitable means for adjustably mounting it on a yoke stud *c*.

One of the blocks or heads, preferably the floating block or head 2, is formed on the 90 inner side facing the block 1, with a longitudinal guiding groove 13, and a guide rod 14, loosely engaging at one end with said groove, is fastened at the other end to the other block. This guide rod, while it permits the block or head 2 to rock sidewise so as to maintain true contact between the brush 8 and the commutator or rotary contact member *a* and to move lengthwise in a radial direction relative to the commutator, 95 prevents its shifting bodily sidewise and maintains it in proper working position on the commutator. It also serves as a strut to prevent the brush from being shifted out of place toward the block or head 1 by the 100 rotation of the commutator in the direction indicated by the arrow on Fig. 1.

The blocks 1 and 2 are preferably connect-

ed by a flexible electric conductor 16, to carry the current between the brush 8 and stud *c* independently of the springs 5.

The brush supporting stud *c* is adjusted 5 on the yoke *b*, and the brush holder is adjusted on the stud, so that the brush 8 will stand radially relative to the commutator or rotary contact member *a*, as shown in Fig. 1, in proper position to engage with 10 its peripheral working face, and the springs 5 will be flexed sufficiently to maintain a lightly yielding contact between the brush and commutator, and prevent sparking.

In the operation of the brush holder, the 15 brush adjusts itself automatically to maintain uniform and effective electric contact between the entire area of its working face and the opposing working face of the commutator or rotary electric contact member. 20 The pressure of the outwardly flexed springs 5 being evenly distributed over the working face of the brush, causes it and the working face of the commutator or rotary contact member to wear evenly, the brush rocking 25 freely sidewise and yielding radially to compensate for any irregularities and eccentricity in the working face of the commutator or rotary contact member.

The blocks or heads 1 and 2 may be connected by one or more springs 5 arranged substantially as shown, to permit the required movements of the brush 8 and to maintain it in proper position relative to the commutator or rotary contact member *a*.

30 Various modifications in the details of construction and arrangement of parts of the brush holder and in the mounting of the same, may be made, without departure from the principle and scope of the invention as defined in the following claims.

I claim:

1. In an electric brush holder the combination of a stationary head, a floating brush-supporting head, and a number of 45 substantially parallel springs connecting the heads with each other.

2. In an electric brush holder the combination of a relatively stationary head, a floating brush-supporting head, and substantially parallel helical springs connecting the heads with each other.

3. In an electric brush holder the combination of a relatively stationary head, a floating brush supporting head, an elastic 55 connection between the heads permitting a sidewise rocking movement of the floating head and yielding movement thereof in a radial direction relative to the rotary contact member with which the brush engages.

60 4. In an electric brush holder the combination

of a stationary head, a floating brush-supporting head, an elastic connection between the heads permitting lateral rocking and radial movements of the floating head, and guiding means preventing lateral displacement of the floating head relative to the rotary contact member with which the brush engages. 65

5. In an electric brush holder the combination of stationary and floating heads, 70 parallel springs connecting said heads, and a rod secured at one end to one head and having a loose pivotal and sliding connection at the other end with the other head, which is movable thereon toward and from 75 the rotary contact member with which the brush engages.

6. In an electric brush holder the combination of stationary and floating heads formed with aligned countersunk holes, a 80 helical spring seated in said holes, and screws engaging the convolutions of the springs adjacent their ends and securing them in the heads.

7. In an electric brush holder the combination of a relatively stationary head provided with a clamping collar for angularly adjustable mounting on a brush-supporting stud, a floating brush-supporting head, and a spring connecting the heads with each 90 other.

8. In an electric brush holder the combination of stationary and floating electric conductor heads, means for fastening an electric brush to the floating head, and a spring and flexible electric conductor connections between said heads. 95

9. In combination with a rotary electric contact member and a brush-supporting stud parallel with and adjustable toward and 100 from the axis of the rotary member, a brush holder comprising a relatively stationary head provided with a clamping collar for angularly adjustable mounting on said stud, a floating head provided with means for fastening a brush thereto, and parallel springs 105 connecting said heads with each other.

10. An electric brush holder comprising a relatively stationary head, a floating brush-supporting head having a longitudinal guiding groove in the side toward the other head, parallel springs fastened at the ends to and connecting said heads, and a strut and guide rod fastened at one end to the stationary head and engaging at the other end with 115 the groove in the floating head.

In witness whereof I hereto affix my signature.

ERNEST BUEROSSE.
